ATTORNEYS.

UNITED STATES PATENT OFFICE.

JAMES K. McGUKIN, OF NEWARK, NEW JERSEY.

SHUTTER-WORKER.

SPECIFICATION forming part of Letters Patent No. 392,214, dated November 6, 1888.

Application filed January 14, 1888. Serial No. 260,681. (No model.)

To all whom it may concern:

Be it known that I, JAMES K. McGUKIN, of Newark, in the county of Essex and State of New Jersey, have invented a new and Improved 5 Shutter-Worker, of which the following is a full, clear, and exact description.

My invention relates to an improvement in shutter-workers, and has for its object to provide a simple, cheap, readily applied, and effective article, whereby a shutter may be held partially or entirely open, and which may be conveniently operated from the room with the windows closed.

The invention consists in the construction 15 and combination of the several parts, as will be hereinafter fully set forth, and pointed out in the claims.

Reference is to be had to the accompanying drawings, forming a part of this specification, 20 in which similar letters of reference indicate corresponding parts in all the figures.

Figure 1 is a transverse section through a portion of a window casing and a blind, illustrating the application of the invention. Fig. 25 2 is a longitudinal section through the applied device. Fig. 3 is a transverse section taken on line 3 3 of Fig. 1, and Figs. 4 and 5 are enlarged detail views.

In carrying out the invention, A represents 30 the sill of a window, a the inner projecting portion, and a' the usual beading. Transversely the sill at each side and through the beading a tube, B, is projected supported in any approved manner at its outer end upon 35 the sill, as illustrated at a² in Fig. 1, which tube outside the said beading is open on top.

Within the outer tube, B, a second tube, D, is concentrically arranged, the inner tube being of a diameter to readily slide in the outer 40 tube and provided at its closed inner end with a longitudinal spirally-twisted bore, b, within which bore a spiral rod, D', is entered, the movement whereof is limited by a suitable stop, in order that the rod may not be turned 45 entirely from its casing.

Upon the inner end of the spiral rod D' a knob, d, is rigidly secured, and upon a spindle fastened to said fixed knob a second knob, d', is held to revolve, as illustrated in Fig. 2. The 50 end d² of the rod D' adjacent to the fixed knob

is of a diameter equal to the diameter of the tube D, for a purpose hereinafter set forth.

In the end of the outer tube, B, upon the top a transverse slot, e, is cut, (shown more clearly in dotted lines in Fig. 4,) and upon the 55 tube at this point a collar, E, is secured by a set-screw or otherwise, provided upon the upper side with an aperture, e', registering and extending parallel with the said slot e. The upper apertured section of the collar projects 60 beyond the body at each side, which projections are provided with aligning segmental recesses e² and e³. Through the aperture e' a cylindrical rod, H, is projected provided with a concavity, h, in one face, which concavity is 65 designed to register with the slot e. The rod H, designed to act as a cam, is retained in position by a pin passing through one end and a hinged handle, h', at the opposite end, and the revolution of the cam is limited by contact of 70 the aforesaid pin and handle with the side walls of the recesses e² and e³, as shown in Figs. 3 and 4. When the cam is in a locked position, the handle h' hangs perpendicularly downward, as shown in Figs. 3 and 5, and enters 75 a slot, h², whereby it is kept from lateral movement. To the outer end of the inner tube at the top an upwardly-inclined strap, k, is brazed, soldered, or otherwise attached, adapted to project outward from the tube, to which one 80 end of a radial bar, K, is pivoted, the other end of said bar being pivoted to a plate, k', fastened to the inner face of the shutter near the hinged side.

In operation, the shutter being closed, as in 85 Fig. 2, the cam-handle is turned from the position illustrated in Fig. 5 to that shown in Fig. 4, which brings the cavity in the cam-rod over the slot in the outer tube, whereby the inner tube is left free to slide. The loose knob 90 is now grasped and the spiral rod drawn out its length as far as desired. This having been effected, the fixed knob is grasped and the rod pushed outward, which movement carries with it the inner tube, which acting upon the radial 95 bar opens the shutter back, as illustrated in Fig. 1. The enlarged end of the spiral rod will have now entered the outer tube, and upon turning the cam-rod to its first position (illustrated in Fig. 3) the same is caused to bind 100

upon the enlarged surface, holding the spiral rod in a fixed position. In closing, the cam is released, the spiral rod drawn inward, the cam again locked upon the inner tube, and the spiral rod is run into the same.

When the device is used in connection with heavy shutters, the twist of the rod and the rod-easing may be graduated to suit the emergency without departing from the spirit of the invention. The knobs may also be ornamented or plain, or of any preferred construction.

Having thus fully described my invention, I claim as new and desire to secure by Letters Patent—

1. In a shutter-worker, the combination, with an outer tube or casing, of an inner concentric tube having a spiral bore, a radial arm attached to the inner tube, a spiral rod adapted to the bore of the inner tube and provided with a knob, and means for clamping said inner tube and rod, substantially as shown and described.

2. In a shutter-worker, the combination, with an outer tube or easing and an inner sliding

25 tube having a spiral bore, of a spiral rod working in the bore of the inner tube and provided

with a fixed knob on its outer end, and a loose knob pivoted on the outer surface of the fixed knob, substantially as described.

3. In a shutter-worker, the combination, with 30 an outer tube having a slot near the inner end, of an inner concentric tube having a spiral bore, a radial arm attached to said inner tube at the outer end, a spiral rod entering the spiral bore of the inner tube provided with a knob, a horizontally-apertured collar fixed upon the outer tube over the slot, and a cam-rod rotating in the collar and in the slot of the outer tube, substantially as shown and described.

4. In a shutter-worker, the combination, with an outer tube or easing having a transverse slot and a sliding tube in the outer tube or easing, of a collar secured to the said easing or outer tube over the slot therein, and a rod having a cavity in one side fitted to turn in the said collar and provided with a handle, substantially as described.

JAMES K. McGUKIN.
